UNITED STATES PATENT OFFICE.

BURTON L. HUNTER, OF MINNEAPOLIS, MINNESOTA, ASSIGNOR, BY MESNE ASSIGNMENTS, TO SPEEDPAK DISPENSER CORPORATION, OF MINNEAPOLIS, MINNESOTA, A CORPORATION OF DELAWARE.

ICE-CREAM-CARTON FILLER.

Application filed June 18, 1926. Serial No. 116,833.

My present invention provides an extremely simple and highly efficient ice cream carton filler and is particularly designed as an improvement on that type of ice cream carton filler disclosed and claimed in my pending applications, one filed April 1, 1925, under Serial Number 19,833 and the other filed Sept. 10, 1925 under Serial Number 55,517, and both entitled "Ice cream carton fillers."

Nevertheless the present invention is capable of general use wherever it may be found applicable to devices for filling cartons or the like with ice cream or similar plastic substances and, generally stated, the invention consists of the novel devices, combinations of devices and arrangement of parts hereinafter described and defined in the claims.

In the manipulation of ice cream carton fillers it is highly important for sanitary reasons that in the use of a device to fill cartons with ice cream the parts that come into contact with the ice cream be not handled, that is, directly engaged with the hands; and it is to this feature that the present invention is primarily and successfully directed.

In the accompanying drawings which illustrate a commercial form of the device, like characters indicate like parts throughout the several views.

Referring to the drawings:

Fig. 1 is a side elevation of the improved carton filler, some parts being broken away and some parts being sectioned;

Fig. 2 is an axial section on the line 2—2 of Fig. 1, some parts being shown in full and some parts being broken away;

Fig. 3 is a horizontal section taken on the line 3—3 of Fig. 1; and

Fig. 4 is a view partly in section on the line 4—4 of Fig. 2, with some parts shown in full, and showing the device opened up or adjusted for removal of the filled carton and for the insertion of an empty carton.

The character A indicates a cylindrical paper carton filled with ice cream α , as shown in Figs. 2 and 3. This carton is of such size that it may be quite freely slipped into a cylindrical metal shell 5 that serves as a carton holder. In its lower edge this shell 5 is provided with circumferentially spaced teeth 6 in cylindrical arrangement so

that they are adapted to cut their way 55 readily through a body of ice cream contained in a can or like receptacle. At the base of its teeth the shell 5 is shown as slightly contracted to afford a stop shoulder at 7 that limits the downward movement of 60 the carton A so that its upper portion will normally project considerably above the top of said shell. The numeral 8 indicates diametrically extended cutting wires, of which there are shown two, extended across the 65 bottom of the shell 5 in the plane of its stop shoulder 7.

For co-operation with the shell or carton holder proper 5 there is a cylindrical cap 9 of the same diameter as the shell 5 and of such depth that it will fit over the projecting portion of the carton A when the latter is inserted in the shell 5. This cap 9 has an axially projecting stem or bar 10 equipped at its outer end with a hand piece 11. The 70 web of the cap 9 is shown as provided with several air escape passages formed in upset thimbles 12 which, as shown, are utilized to hold in position a transparent plate 13, such as celluloid, and a thin metal plate 14. The 75 plate 14 and the web of the cap 9 are shown as provided with coincident sight openings 80 15 so that the operator can observe when the carton has been filled. The shell 5 is shown as provided with small air ports 16, which 85 feature is disclosed and claimed in my prior application Ser. No. 55,517 more fully identified above.

As an important feature of this invention heretofore referred to in a general way, the 90 shell 5 and cap 9 are connected in such a way that the two may be separated axially and the former turned into a position at an angle to the latter so that an empty carton may be placed in the shell 5 or a filled carton removed therefrom; and, moreover, this connection is such that the above movements may be accomplished without placing the hands in contact with any of the surface that comes into contact with the ice cream. 95 In this preferred arrangement, the connection is made by a flat bail or U-shaped lever 17 that loosely embraces the sides of the cap 9 and is pivotally connected to the sides of the shell 5 by pivot trunnions 18. The bar 100 or handle 10 of the cap 9 is arranged to slide freely through a passage formed in the top of the bail 17. In its sides the bail 17 105

is formed with longitudinal slots 19 and the cap 9, at diametrically opposite points, is provided with outwardly projecting studs or lugs 20 that work freely in the slots 19.

5 The bail 17 is arranged to swing from its vertical position in one direction only, and as shown, this is accomplished by stop projections 21 on the pivoted ends of said bail that engage with stop lugs 22 on the sides.

10 The numeral 23 indicates an outwardly spring-pressed latch lever applied to the handle 10 and engageable with the bail through a notch 24 formed in the latter. This latch lever will serve to lock the stem 11 against upward sliding movements and thus hold the cap in working position against the shell 5, as best shown in Fig. 1.

In describing the use of the device, attention is first called to Fig. 4, by reference to which it will be noted that when the latch lever 23 is pressed inward to release the cap 9 from the shell 5, the latter may be slid upward, and when turned into a horizontal position in the right direction, the shell 5 will, under the action of gravity, assume an upright position at an angle to the stem and axis of the cap and in which position the carton may be applied within the shell or removed therefrom. This, as is evident, may be accomplished without engaging the hands either with the shell 5 or cap 9. When a filled carton is exposed, as shown in Fig. 4, its upper edge may be engaged with the hand and the carton rotated so as to trim off the ice cream at the bottom of the carton, and, of course, the filled carton may then be readily removed and replaced by an empty carton.

40 The carton would be placed in the shell 5 when still in the position shown in Fig. 4, and then when the stem 10 and cap 9 are rotated while in an oblique position, the shell 5 will, under the action of gravity, assume a position in axial alignment with the 45 cap, and then by taking hold of the bail 17 the shell 5 may be drawn upward and the projecting end of the carton inserted into the cap. When the cap has been placed against the shell the latch lever 23 will lock 50 the cap to the shell against axial movements.

It is important to note that the lugs 20 on the cap 9 hold the cap and container 5 against oscillatory movements around their common axis when aligned and assembled to receive the ice cream. Hence, when the device is oscillated as an entirety in forcing the same into the cream, there will be no lost motion and the container will be given whatever oscillatory movement is applied to the cap by the manipulation of the operating handle. Moreover, the cap and the container will be locked together whether or not a carton is in position.

The device described has, in practice, been found convenient and satisfactory for the

purposes had in view and, moreover, it is sanitary in that the cream-contacting parts need not be handled in the filling operation and that the entire device may be easily washed and sterilized.

Another important fact may be noted, to wit: that the cap is guided for true straight-line movements on the yoke-like lever and that the said yoke-like lever is stopped in a position with the stem of the cap coincident with the axis of the cylindrical container, so that when the cap is slid on the yoke, it will go into true registration with the container and will freely telescope around the projecting upper end of the 75 80 carton.

What I claim is:

1. An ice cream carton filler comprising a cylindrical carton container, a cap for said container, a stem projecting from said cap, and a lever in the form of a yoke pivoted to the sides of said container and slidable on said stem, said yoke in its arms having longitudinal slots and said cap having diametrically projecting lugs working in said slots.

2. An ice cream carton filler comprising a cylindrical container formed smooth at its upper edge and provided with teeth at its lower edge, a cutting wire extending 95 across the container at the base of its teeth, a bail-like lever having its arms pivoted to the sides of said container and formed in its arms above its pivot, longitudinal slots, a cap of the same diameter as said container, and a stem secured to and projecting axially from said cap and working slidably 100 through said bail-like lever, said cap having outstanding lugs working in the slots of said lever, said container having stops that 105 engage said lever and permit the same to move on its pivots in one direction only.

3. The structure defined in claim 2 in further combination with means for locking said cap in engagement with said container against axial movements in respect thereto. 110

4. An ice cream carton filler comprising a cylindrical carton container, a cap for said container, a stem projecting from said cap, 115 a lever pivoted to said container and slidable on said stem, and means for locking said lever against sliding movement on said stem.

5. An ice cream carton filler comprising a cylindrical carton container, a cap for said container, a stem projecting from said cap, a lever in the form of a yoke pivoted to the sides of said container and slidable on said stem, and a latch applied to said yoke to lock said stem against sliding movements thereon. 125

6. The structure defined in claim 1 in further combination with a latch applied to said stem and engageable with said yoke to lock the latter against sliding movements 130

on said stem and to hold said cap in co-operative engagement with said container.

7. The structure defined in claim 1 in which said lugs and slots hold said cap 5 against rotation around its axis.

8. An ice cream carton filler comprising a cylindrical carton container, a cap for said container, a stem projecting from said cap, a yoke-like lever pivoted to the sides of said 10 container, said cap having sliding engagement with said yoke but by said yoke held against rotation around its axis, said container being capable of oscillation on its pivotal connection to said yoke-like lever 15 when said cap is retracted, to thereby carry said cap out of alignment with said cylindrical container.

9. The structure defined in claim 8 in further combination with stop devices permitting 20 oscillation of said container on its pivotal connection to said yoke-like lever, in one direction only, from a position in axial alignment with said cap.

10. An ice cream carton filler comprising 25 a cylindrical carton container having a cutting edge on its lower end, a cap on the container for holding a carton in the container against removal through the open top thereof, a stem projecting from the cap, and a 30 lever pivoted to the container, said stem hav-

ing longitudinal sliding engagement with the lever.

11. An ice cream carton filler comprising a cylindrical carton container having a cutting edge on its lower end, a cap on the container 35 for holding a carton in the container against removal through the open top thereof, a stem projecting from the cap, and a lever in the form of a yoke pivoted to the sides of the container, said stem having 40 longitudinal sliding engagement with the lever.

12. The structure defined in claim 10 in further combination with means for locking 45 the cap to the container.

13. The structure defined in claim 11 in further combination with means for locking the cap to the container against axial movement in respect thereto.

14. An ice cream carton filler comprising 50 a cylindrical carton container having a cutting edge on its lower end, a cap on the container for holding a carton in the container against removal through the open top thereof, a stem projecting from the cap, and a 55 lever pivoted to the container, said stem and cap having longitudinal sliding engagement with the lever.

In testimony whereof I affix my signature.
BURTON L. HUNTLEY.
